DESIGN FOR A TEXTILE FABRIC

Alexander Kohut, New York, N. Y., assignor to Croydon Fabrics, New York, N. Y., a corporation of New York

Application November 7, 1933. Serial No. 49,663

Term of patent 3½ years

To all whom it may concern:

Be it known that I, ALEXANDER KOHUT, a citizen of United States, residing at the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design. A single unit of my design is substantially shown in the drawing.

I claim:

The ornamental design for a textile fabric, substantially as shown and described.

ALEXANDER KOHUT.
